FOOTBALL DOWN AND BALL MARKER

Michael B. Komendat, Jr., 524 Plum St.,
Fairport Harbor, Ohio 44077

Filed Sept. 22, 1970, Ser. No. 25,146

Term of patent 14 years

Int. Cl. D21—02

U.S. Cl. D34—5

FIG. 2

FIG. 1 is a front elevational view of a football down and ball marker embodying my new design, the opposite side being identical; and FIG. 2 is an edge view thereof.

I claim:

The ornamental design for a football down and ball marker, as shown and described.
